UNITED STATES PATENT OFFICE.

WILLIAM GEORGE GIBBINS, OF FOREST GATE, ENGLAND.

WASHING, DYEING, AND SOFTENING MACHINE.

1,052,911.

Specification of Letters Patent. Patented Feb. 11, 1913.

Application filed June 27, 1911. Serial No. 635,570.

To all whom it may concern:

Be it known that I, WILLIAM GEORGE GIBBINS, a subject of the King of Great Britain and Ireland, residing at Forest Gate, in the county of Essex, England, have invented Improvements in Washing, Dyeing, and Softening Machines, of which the following is a specification.

This invention relates to improvements in machines for washing, dyeing or softening any material that requires so treating.

The object of the invention is to produce a machine that by a simple readjustment will operate upon any class of material from the most delicate fabric such as lace, silks, flannel, wool, to the coarser and heavier goods such as meat cloths, filter press cloths, material for flock-making, skins, hides, etc., without any damage to the fabric however delicate and without causing shrinkage of flannel goods.

The apparatus comprises a cylindrical or rectangular shaped vessel, portions of which may be perforated, mounted in suitably shaped frames or standards to swing or oscillate through 360° or thereabout. The vessel may have an outer casing to contain the washing liquor. A loose shaft passes through the center of the vessel and bearing closely against, but not attached to, one side of this shaft and parallel to it is a partition that is fixed to the vessel and which moves with it. Mounted upon the opposite side of this shaft and fixed to it is a movable partition which can be oscillated through the shaft from the outside of vessel, be secured to the vessel or be held vertical by springs. The partition which is permanently fixed to the oscillating vessel is built up of longitudinal ribs some or all of which may be of convex shape and the other partition of longitudinal ribs some or all of which are of concave shape. An overflow arrangement is provided to allow the dirty water to pass out of the vessel while the clean is running in.

Referring to the accompanying drawings, Figure 1 is a front elevation of a washing, dyeing or softening machine according to this invention; Figs. 2 and 3 are elevations of the opposite ends of the machine. Fig. 4 is a central transverse section; and Figs. 4^a and 4^b are detail views of the convex and concave ribs respectively. Fig. 5 is a detail section.

55 *a* is the liquor containing outer casing extending centrally through which is a shaft *b*

on which the vessel *c* is freely mounted within the casing.

c¹ *c²* are doorways for loading and discharging the vessel *c*; they are closed by doors not shown.

The shaft *b* is provided with a sleeve *b¹* of brass or other material not liable to cause damage to the articles under treatment.

d is the partition that is fixed to the vessel *c* and built up of longitudinal ribs some of which, namely *d¹*, are of double convex shape, Fig. 4^a.

f is the movable partition fixed to the shaft *b* and constituted by longitudinal ribs of double concave shape, Fig. 4^b that are fixed at the required distance apart upon bolts *f¹* screwed through the sleeve *b¹* into the shaft *b* (see Fig. 4).

The vessel *c* is oscillated from belt pulleys *g* on a counter shaft *h* through a pinion *m*, an idle wheel *n*, and a gear wheel *o* fixed on a trunnion *p* projecting from one of the end walls *q* of the vessel *c* and through which trunnion a portion of the shaft *b* of reduced diameter extends.

The belt pulleys *g* comprise two loose and a fast pulley, and the belt shifter *r* for effecting the reversal of the direction of drive at the desired times is actuated by cams *s* fixed to the wheel *o* and a lever *p^x* secured to the rocking shaft *t* of the belt shifter, the positions of the cams *s* and the parts of the lever *p^x* with which they come in contact being such that the vessel *c* oscillates through only part of a revolution and the partition *d* stops before it reaches the vertical position.

r¹ is a spring pressed pin to insure the belts being quickly and completely moved into correct positions.

u is a crank arm fixed on the end of the shaft *b* beyond the wheel *o* and adapted to be secured to such wheel by a pin *v*, as shown in Fig. 2, in which case the partition *f* moves with the vessel *c*, the relative position of the partitions *d* and *f* being indicated in dotted lines. Fixed on the other end of the shaft *b* is a lever *1* that by a pin *2* can be fixed to an arm *3*, as shown, which is freely mounted on the shaft *b* at one end and at its other end is formed with a lug or eye *3¹* that embraces curved bar *4* on which are mounted springs *5* that constantly tend to keep the arm *3* in a vertical position, in which case the movable partition *f* is also vertical as indicated in dotted lines in

Fig. 3. The lever 1 can be released from the arm 3 and be secured to a wheel 6 freely mounted on the shaft *b*, by passing the pin 2 through a hole 7, in the other end of the 5 arm 1, and into a hole 8 formed therefor in the wheel 6. The wheel 6 is driven by a pinion 9 on the shaft *b*, of smaller diameter than the pinion *m*, and an idle wheel 10, so that when the lever 1 is fixed to the wheel 10 6 as described, the partition *f* moves with the vessel *c* but at a slower speed.

Clean water is supplied to the casing *a* from a main 13 and dirty water can simultaneously flow away therefrom through 15 branches 12 and an outlet pipe 11, the end of which is turned up so that the escaping water can be seen as it trickles over the pipe end and in this way an indication is obtained when the washing is completed. In 20 Fig. 1 the outlet pipe is shown connected to a T-piece 11^a, the one branch 11^b of which is turned up and the other branch of which is fitted with a cock 11^c; so long as the cock 11^c is closed dirty water from the bottom 25 of the apparatus overflows from the branch 11^b, the water in the apparatus being maintained at a corresponding level, while if the cock 11^c be opened the apparatus can be completely drained. The branch 11^b may 30 be fitted with a cock which can be closed when goods are being boiled under pressure.

In Fig. 1, for the sake of clearness, the upper part of the casing *a* is removed. 35 When goods require to be squeezed, they are loaded on either side of the partition *d* fixed to the vessel and the movable partition *f* is held vertical by the springs 5, Fig. 3, then as the vessel *c* swings around the 40 goods are lifted up by the fixed partition *d* and pressed against the movable partition *f* which yields to the pressure. The vessel is reversed and the goods on the opposite side of the partition are subjected to the 45 same action. When goods do not require a squeeze but require rubbing, the movable partition *f* is secured to the wheel 6 which is revolving at a slower speed than the vessel *c*. The effect is that as the vessel swings 50 around and the fixed convex partition *d* rises above the horizontal, the goods move downward, and longitudinally outward, until they reach the movable and concave partition *f* when they move downward and longitudinally inward but do not reach the washing liquor as the vessel will be reversed before the slower moving partition reaches the liquor. By these movements a generous rubbing action is imparted to the goods. 55 The vessel is then reversed, the movable partition *f* rises and the fixed one *d* falls with the swing of the machine and the articles are again rubbed as they move downward to the washing liquor; so that there is 60 a double rubbing action intermediate of

plunging in the washing liquor. On the other side the goods will be subjected to a similar rubbing action intermediate of plunging in the liquor. When washing goods that require more movement than in 70 either of the foregoing methods, the movable partition *f* is fixed to the vessel by the arm *u* and pin *v*, as shown in Fig. 2, and moves with it at the same speed as the vessel. This divides the machine into two 75 halves, so that, as the vessel swings, the goods are lifted by each partition and rub over the ribs of partitions into the washing liquor. As the partition *d* always stops before reaching an upwardly extending vertical position, the goods when lifted move down toward the water over the ribs of the partitions and cannot drop direct from the lifting partition into the water as happens in machines of the type in which a drum divided by a fixed perforated or ribbed partition makes a number of complete revolutions first in one direction and then in the other.

For dyeing articles (for example wearing apparel) or skins, the machine is set so as to impart a squeeze as described in the first method. For softening leather, skins or other articles (for example wearing apparel) the machine is set so that the goods 95 get the maximum amount of rubbing as described in the second or third method.

In details of construction the machine can be other than as in the example shown without departure from the invention.

In the claims the machine will be referred to as a washing machine but it is to be understood that this term is intended to include machines used for dyeing, softening or otherwise treating goods with liquor.

What I claim is:—

1. A washing machine comprising an oscillating vessel, a radial partition within and fixed to said vessel, a second radial partition within said vessel, means for yieldingly supporting said second partition in a stationary position and means for positively moving said second partition.

2. A washing machine comprising an oscillating vessel, a radial partition within and fixed to said vessel, a second radial partition within said vessel, means for yieldingly supporting said second partition in a stationary position and means for positively moving said second partition at the same 110 speed as the vessel or at a slower speed.

3. A washing machine comprising an oscillating vessel, within said vessel a radial partition having ribs the faces of which are longitudinally concave and a second radial 125 partition having ribs the faces of which are longitudinally convex, the said partitions extending from the axis into proximity to the walls of the vessel and being adapted to move in the same direction as the vessel.

4. A washing machine comprising a liquor containing casing, an oscillating vessel therein, a ribbed radial partition fixed in said vessel, and a ribbed radial partition adapted to be oscillated at a slower speed than the vessel so that the goods are subjected to a double rubbing action against the ribs intermediate of being plunged into the liquor.
5. A washing machine comprising a liquor containing casing, a perforated oscillating vessel, a shaft running through said vessel, a partition fixed to the vessel and radially extending from the shaft to the wall of the vessel, another similarly arranged partition fixed on the shaft, means for oscillating, when desired, the vessel at one speed and the shaft at a slower speed and means for securing at will the latter partition to the vessel, or to a device adapted to yieldingly support it in a vertical position.
6. A washing machine comprising a liquor containing casing, a perforated oscillating vessel, a shaft running through said vessel, a partition fixed to the vessel and radially extending from the shaft to the wall of the vessel, another similarly arranged partition fixed on the shaft, gear wheels secured to the vessel and its shaft and adapted to be driven at different speeds through a common countershaft and automatic reversing mechanism.
7. A washing machine comprising a liquor containing casing, an oscillating vessel therein, a ribbed radial partition fixed in said vessel, and a ribbed radial partition adapted to be oscillated at a slower speed than the vessel so that the goods are subjected to a double rubbing action against the ribs intermediate of being plunged into the liquor and means for supplying clean liquor thereto and allowing the overflow of dirty liquor therefrom.
8. A washing machine comprising a liquor containing casing, a perforated oscillating vessel, a shaft running through said vessel, a partition fixed to the vessel and radially extending from the shaft to the wall of the vessel another similarly arranged partition fixed on the shaft, gear wheels secured to the vessel and its shaft and adapted to be driven at different speeds through a common countershaft and automatic reversing mechanism and means for securing at will the latter partition to the vessel, or to a device adapted to yieldingly support it in a vertical position.

Signed at Hudson Bay Works, Warton Rd, Stratford, London E. this 13th day of June 1911.
